UNITED STATES PATENT OFFICE.

CHARLES H. GREENWOOD, OF BELVIDERE, ILLINOIS.

SEWING MACHINE.

Application filed March 2, 1923, Serial No. 622,306. Renewed June 14, 1928.

This invention relates to sewing machines and more particularly to improvements in the feed and rotary hook and driving means for the same.

5 The objects of the invention are to provide a simple and positive driving mechanism for operating both the rotary hook and the feed to so construct the rotary hook and arrange the location of the same with reference to the 10 feed and the needle as to produce a smaller loop; to provide a hook and bobbin case of such construction that the bobbin may be placed either end up in the bobbin case without affecting the tension upon the lower 15 thread; to provide means for permitting the bobbin to be easily lifted from the bobbin case without requiring a bobbin ejector; to provide means for causing a self threading of the lower or bobbin thread through the 20 tension upon the bobbin case; to provide a simple and easily operated stitch adjusting mechanism cooperating with the feed drive; to provide suitable means for keeping the 25 working parts of the mechanism lubricated and to generally improve and simplify mechanism of this character; and to provide a machine which is practically fool proof.

The above and other objects may be attained by constructing the mechanism in the 30 manner illustrated in the accompanying drawings, in which—

Figure 1 is a vertical, longitudinal, sectional view through a sewing machine embodying the invention;

5 Fig. 2, a plan sectional view approximately on the line 2—2, Fig. 1;

Fig. 3, a section on the line 3—3, Fig. 2;

Fig. 4, a section on the line 4—4, Fig. 2;

0 Fig. 5, a section on the line 5—5, Fig. 2;

Fig. 6, a section on the line 6—6, Fig. 2;

Fig. 7, a plan view of the needle plate;

Fig. 8, an edge view of the same;

Fig. 9, a plan view of the rotary hook and bobbin case;

5 Fig. 10, a vertical sectional view through the same;

Fig. 11, a sectional view through the needle plate;

0 Fig. 12, a plan view of the tension mechanism;

Fig. 13, a side elevation of the same;

Fig. 14, a section on the line 14—14, Fig. 12; and

Figs. 15 and 16, side elevations of the eccentric mechanisms for operating the feed dog.

Similar numerals of reference indicate cor-

responding parts throughout the drawings.

The arm 1 is provided with the usual head 2 and is mounted upon the base plate 3 as by the flanges 4 at the lower end of the neck. 60 The drive shaft 5 is journaled through the arm in the usual manner and has mounted thereon a bevel gear 6 meshing with a similar gear 7 upon the vertical shaft 8, which is journaled at its upper end in a bearing 9 65 formed upon the interior of the hollow arm and at its lower end in a bearing 10 depending from the under side of the base plate, bushings 11 being provided in said bearings. 70

A hollow shaft 12 is journaled at its opposite end portions within the bearings 13 and 14 formed in the depending walls 15 and 16 respectively, which are preferably formed integral with the base plate 3. A sleeve 17 is fixed in the forward end of the 75 tubular shaft 12 as by a screw 18 or the like, and a similar sleeve 19 is fixed in the rear end of the tubular shaft as by the screw 20.

A shaft 21 is journaled at opposite ends in the sleeves 17 and 19 and is provided at its 80 rear end with a bevel gear 22 which meshes with a similar gear 23 fixed upon the lower end of the shaft 8.

A bevel gear 24 is fixed upon the forward 85 end of the shaft 21 and meshes with the bevel pinion 25 upon the lower end of the spindle 26 of the rotary loop taker 27, said spindle being journaled in a suitable bearing 28 provided upon the transverse wall 29 which depends from the base plate 3. The gear 24 is 90 preferably larger than the pinion 25.

For the purpose of keeping all of the above mentioned bevel gears properly lubricated, oil cups or wells 30 are located at suitable points adjacent to the gears and provided 95 with wicks 31 engaging the tooth surfaces of one gear of each set.

A thin film of oil will thus be formed upon each of the gears which contacts with one of the wicks and the cooperating gear of each 100 set will also be properly oiled as it rotates in mesh therewith. The interior of the hollow shaft 12 also constitutes an oil well for properly oiling the bearings of the shaft 21 and the parts associated therewith, an oil 105 hole 30' being provided in the hollow shaft 12 for filling said well.

An arm 32 is fixed upon the sleeve 19 and extends outward through a slot 33 in the casting 34 which is connected to the base plate 110 and covers the mechanism. An adjusting screw 35 is journaled through an opening

36 in the base plate and provided with the enlarged, knurled head 37. The screw is reduced as at 38 to receive the bifurcated plate 39 mounted upon the under side of the base plate and connected thereto as by the screw 40.

It will thus be seen that the screw is journaled in the base plate and may be rotated in either direction by means of the knurled head, without raising or lowering the screw in its bearing and without permitting the screw to be withdrawn, excepting upon removal of the bifurcated plate 39.

A nut 41 is mounted upon the threaded portion of the adjusting screw and provided with a radial flange 42 carrying a pin 43 which is extended through the elongated slot 44 in the arm 32. Thus by rotating the screw to raise or lower the nut 41, the sleeve 19, and through it the hollow shaft 12 and sleeve 17 will be rocked in unison.

The gear 24 is provided with the enlarged hub portion 45 upon which is keyed or splined a pair of eccentrics 46 and 47. An eccentric band 48 is journaled upon the eccentric 46 and provided with an upwardly extending arm 49 to which the feed dog 50 is connected as by the screw 51, said arm having a horizontally disposed portion 52, the end portion of which is slidably located within the guide 53 which is formed upon the under side of the base plate.

An eccentric band 54 is mounted upon the eccentric 47 and provided with the tangential rearwardly disposed arm 55, the end portion of which is slidably mounted in the guide 56 provided upon the bottom wall of the casting 34. A link 57 is connected at its lower end to the arm 55 as by the pin 58, the upper end of the link being pivotally connected to a stationary portion of the machine, such as the wall 29 as by the pin 59.

A pair of slotted links 60 are connected at their upper ends to the arm 52, one of said links being mounted upon each side of the arm and a pin 61 fixed in the upper ends of the two links extending through the vertical slot 62 in the arm 52. The lower ends of the links 60 are connected to the arm 55 by the pin 58 which connects said arm to the link 57.

A bent arm 63 is fixed upon the sleeve 17 and the end portion thereof is located between the links 60 and provided with a pin 64 located in the arcuate grooves 65 formed in the links 60, this pin forming a fulcrum upon which the links 60 are rocked by the eccentric movements of the arms 52 and 55 to cause the feed dog 50 to move upward, forward, downward and backward in succession through the slots 66 in the needle plate 67.

In order to change the length of the stitch, the adjusting screw 35 is adjusted as above described, rocking the arm 32 upon the sleeve 19, which in turn rocks the tubular shaft 12

and the sleeve 17, the arm 63 thereon being rocked, changing the fulcrum point 64 providing for a longer or shorter horizontal movement of the feed dog 50.

The cup shaped body portion 27 of the loop taker is provided with the inwardly disposed, annular rim 68 extending substantially around the same to engage the annular groove 69 in the supporting plate 70 of the bobbin case 71. One half of this rim is removable as shown at 72 and preferably comprises the upper and lower spaced plates 72 and 73 between which is located a sheet of felt or the like 74, the lower plate 73 being provided with one or more openings 75 communicating with the oil well 76 formed in the body portion 27, thus providing lubrication to the groove 69 of the bobbin case supporting plate.

One end of the rim or flange 68 is provided with the inwardly directed, loop seizing hook 77 and the other end of the rim is formed with a loop detaining shoulder 78 which forms together with the hook 77, an open throat 79 into which the needle loops are directed for passages about the bobbin case.

The bobbin case supporting plate 70 is peripherally cut away at 80 to form the stationary hook 81 which catches the lower part of the needle loop for detention in the opening 80 until said loop has been carried about the bobbin case and the loop detaining shoulder 78 has reached the cut away extension 80^a of said opening 80, to permit escape of the needle loop. This cut away 80^a provides means for quickly releasing the loop which is a desirable feature in sewing machine construction.

The bobbin case or thread case 71 comprises an open ended cylinder formed integrally with or fixedly mounted upon the supporting plate 70 and having the inwardly disposed, annular flange 82 at its lower end to support the bobbin.

A lug 83 is provided upon the outer edge of the bobbin case at a point adjacent to the opening 80 and arranged to be received within a notch 84 formed in the downturned flange 85 of the needle plate, thus preventing rotation of the bobbin case, while the circular loop taker and hook may freely rotate around the same.

The supporting plate 70 is provided with the cut-out portion 86 within which is mounted the tension comprising the curved block 87 which is spot welded or otherwise connected to the wall of the bobbin case and provided with the enlarged head portion 88 having the curved under edge 89, the forward end thereof being also curved as at 90, terminating in the point 91, spaced from the bobbin case as shown at 92.

A vertical slot 93 is formed in the wall of the bobbin case in alignment with the flat end 94 of the block 87 and a spring 95, curved downward along its edge as shown at 96 and

at its forward end as at 97, is connected to the under side of the head as by the screw 98.

It will be noted that the under side of the head 88 is inclined upwardly away from the slot 93, as shown at 99, the spring 95 forming therewith an upwardly inclined passage for the bobbin thread arranged to direct the thread toward the needle opening 100 in the needle plate 67.

10 It will be seen that the upper edge of the bobbin case adjacent to the point 91 is cut away for a considerable distance from the slot 93 as shown at 101 and a somewhat similar cut-out 102 is formed in the diametrically opposite side of the bobbin case to permit the operator to insert the thumb and finger nails beneath the upper flange of the bobbin to remove the same from the bobbin case, without requiring the use of the usual bobbin ejector.

20 The cut-out 101 also provides a thread guide to guide the thread from the bobbin into the slot 93 and between the spring 95 and head 88 of the tension. The bobbin may be placed in the bobbin case in either position 25 and the loose end of the thread thrown over the cut-out portion 101 of the bobbin case.

As the needle loop passes around the bobbin case, it will take up this loose end of the bobbin thread and carry the same under the

30 point 91 of the head 88 and through the slot 93 of the bobbin case, pulling the end of the thread up between the spring 95 and head 88 of the tension, directing the extremity of the thread toward the needle opening in the needle plate. It will thus be seen that the bobbin case is self-threading, as well as being 35 operative with the bobbin in either position.

In rotary hook machines it is of course necessary to hold the bobbin case against rotation with the loop taker. This requires the engagement of some point upon the bobbin case with a stationary portion of the machine, and each time the loop is carried around the bobbin case the thread is pinched 45 at this point, often causing slack thread to be drawn out after the complete loop is taken.

The take-up will not take care of this extra slack in the thread and it is customary to increase the tension upon the needle thread to 50 prevent this slack in the loop, but in sewing thin material a heavy tension causes the material to pucker.

In my construction, the bobbin case is held against rotation by the lug 83 engaging the 55 notch 84 of the needle plate, and this lug is so located with reference to the hook that the pinch will come at the beginning of the formation of the loop. Thus if any slack thread is drawn out by this pinch, the same 60 will be taken up by the hook and a much lighter tension may thus be used.

By doing away with the usual bobbin ejector, which is ordinarily necessary with the horizontal loop taker, the diameter of the bob-

bin supporting plate is considerably reduced. 65 Since the loop seizing hook projects inwardly, toward the bobbin case, the loop which is formed around the bobbin case is considerably smaller than is possible with the usual form of machine having a bobbin ejector. 70

The loop is further reduced in size by locating the bobbin case as close as is possible to the needle, as illustrated in the drawings, there being only sufficient space to permit removal of the bobbin from the bobbin case 75 without interference by the needle plate.

With this construction, the circular loop taker may be considerably smaller than in the usual construction and the bobbin is located closer to the needle as best illustrated 80 in Fig. 10, thus forming a smaller needle loop.

It will be seen from the above that the driving mechanism for raising and carrying the feed dog is located directly beneath the feed, 85 providing a positive, easy drive which may be easily and readily adjusted for different length of stitch by merely changing the location of the fulcrum 64 through the adjusting screw of the stitch adjusting mechanism. 90

Regardless of the adjustment of the feed mechanism by means of the stitch adjusting device, the feed dog will always move toward the front or operator's side of the needle plate to a point almost contacting with the adjacent edge of the slot therein, thus obviating the possibility of catching the material between the feed dog and the edge of the slot in which it travels; and also to permit the stitch to start at the edge of the material. 100

This action of the feed dog is caused by the drive mechanism for the dog including the links with the arcuate slots 65 in which the fulcrum 64 is adjustable. The slots 65 form the arc of a circle, the center of which is at 105 the center of the shaft 12, upon which the rocker arm 63 is fixed, when the feed dog is at the forward extent of its movement.

Thus by moving the fulcrum 64 to any point in the slots 65, the movement of the feed dog 110 is lengthened or shortened, but the forward end of the travel of the feed dog always remains at the same point.

The rear end of the feed dog will be tilted slightly upward as the feed dog moves up 115 to grasp the material and as it reaches its uppermost position, it will assume a horizontal position. The forward end of the feed dog will thus be inclined slightly downward, forming an open throat between the same and 120 the pressure foot, facilitating the entrance of heavy seams between the feed dog and pressure foot.

The loop taker extending beneath the feed dog will tend to prevent lint from being deposited upon the gears and the bearings of the feed driving mechanism. To further assure 125 the carrying of the lint away from these parts,

a curved guard plate 104 is connected to the arm 49 and guides the lint away from these parts.

I claim:

1. In a sewing machine, a rotary shaft, a pair of eccentrics mounted upon the shaft, an eccentric band upon each eccentric, an upwardly disposed arm upon one band, a feed dog upon the upper end of said arm, a rearwardly disposed arm upon the other band, a link pivoted at its lower end to the rearwardly disposed arm and loosely connected at its upper end to the upwardly extending arm and a fulcrum intermediate the extremities 10 of said link.
2. In a sewing machine, a rotary shaft, a pair of eccentrics mounted upon the shaft, an eccentric band upon each eccentric, an upwardly disposed arm upon one band, a feed dog upon the upper end of said arm, an outwardly disposed arm upon the other band, a link pivoted at its lower end to the outwardly disposed arm and loosely connected at its upper end to the upwardly extending arm, a fulcrum intermediate the extremities of said link, and means for changing the position of the fulcrum to change the length of movement of the feed dog.
3. In a sewing machine, a rotary shaft, a pair of eccentrics mounted upon the shaft, an eccentric band upon each eccentric, an upwardly disposed arm upon one band, a feed dog upon the upper end of said arm, an outwardly disposed arm upon the other band, a link pivoted at its lower end to the outwardly disposed arm and loosely connected at its upper end to the upwardly extending arm, said link having an arcuate slot therein, a tubular rocker shaft journaled upon said rotary 35 shaft, a rocker arm upon said rocker shaft, a pin upon the rocker arm extending into said arcuate slot and means for rocking said rocker shaft and holding it in adjusted position.
4. In a sewing machine, a rotary shaft, a pair of eccentrics mounted upon the shaft, an eccentric band upon each eccentric, an upwardly disposed arm upon one band, a feed dog upon the upper end of said arm, an outwardly disposed arm upon the other band, a link pivoted at its lower end to the out-

wardly disposed arm and loosely connected at its upper end to the upwardly extending arm, said link having an arcuate slot therein, a tubular rocker shaft journaled upon said rotary shaft, a rocker arm upon said rocker shaft, a pin upon the rocker arm extending into said arcuate slot, and an adjusting screw for rocking said rocker shaft and holding it in adjusted position.

5. In a sewing machine, a rotary shaft, a pair of eccentrics mounted upon the shaft, an eccentric band upon each eccentric, an upwardly disposed arm upon one band, a feed dog upon the upper end of said arm, a rearwardly disposed arm upon the other band, a link pivoted at its lower end to the rearwardly disposed arm and loosely connected at its upper end to the upwardly extending arm and a fulcrum intermediate the extremities of said link, and guide means for said arms.

6. In a sewing machine, a rotary shaft, a pair of eccentrics mounted upon the shaft, an eccentric band upon each eccentric, an upwardly disposed arm upon one band, a feed dog upon the upper end of said arm, a rearwardly disposed arm upon the other band, a link pivoted at its lower end to the rearwardly disposed arm and loosely connected at its upper end to the upwardly extending arm and a fulcrum intermediate the extremities of said link, and a swinging support for the rearwardly extending arm.

7. In a sewing machine, a rotary shaft, a pair of eccentrics mounted upon the shaft, an eccentric band upon each eccentric, an upwardly disposed arm upon one band, a feed dog upon the upper end of said arm, a rearwardly disposed arm upon the other band, a link pivoted at its lower end to the rearwardly disposed arm and loosely connected at its upper end to the upwardly extending arm and a fulcrum intermediate the extremities of said link, and a link connected at its upper end to a stationary portion of the machine and at its lower end to the rearwardly disposed arm.

In testimony that I claim the above, I have hereunto subscribed my name.

CHARLES H. GREENWOOD.
